(57) **CLAIM**

The ornamental design for an oil pan, as shown and described.

DESCRIPTION

FIG. 1 is an upper perspective view of an oil pan;
 FIG. 2 is a front elevation view of the design of FIG. 1;
 FIG. 3 is a rear elevation view of the design of FIG. 1;
 FIG. 4 is a right side elevation view of the design of FIG. 1;
 FIG. 5 is a left side elevation view of the design of FIG. 1;
 FIG. 6 is a top plan view of the design of FIG. 1;
 FIG. 7 is a bottom plan view of the design of FIG. 1; and,
 FIG. 8 is a lower perspective view of the design of FIG. 1.
 The broken line disclosure in the drawings depicts
 unclaimed environmental subject matter of the oil pan.

1 Claim, 8 Drawing Sheets(56)
